GLAZING STRIP AND STOP ASSEMBLY

John J. Di Cesare, Jr., and Edward J. Rutkowski, Kenmore, N.Y., assignors to National Gypsum Company, Buffalo, N.Y., a corporation of Delaware

Filed Nov. 27, 1964, Ser. No. 414,060
8 Claims. (Cl. 52—498)

This invention relates to improvements in wall construction, and more particularly to a new and improved glazing strip and stop assembly for supporting a wall panel, such as a glass panel, preferably in a demountable partition wall formed of extruded metal framing members.

A primary object of the invention is to provide such an assembly which is designed to permit easy installation of the glass panel in light openings in partition walls by minimizing or eliminating the need for inserting the panel into a plurality of glazing recesses or channels in the wall frame, as well as by eliminating the necessity of installing the panel in any particular wall erection sequence.

Another object is to provide such an assembly which is designed to facilitate assembling and disassembling thereof, as well as removal of the panel from the wall whenever desired.

A further object is to provide such an assembly which is designed to minimize or eliminate visible fastening means therein for improved appearance.

Additional objects and advantages of the invention will become apparent upon consideration of the following detailed description in conjunction with the accompanying drawings, wherein:

FIG. 1 is a front plan view of a ceiling height, demountable partition wall section having a floor to ceiling window opening in which are removably mounted a pair of glass panels;

FIG. 2 is a section taken along line 2—2 of FIG. 1 and illustrating a floor cornice and rail cap as a preferred means for supporting the glazing beads and lower edges of the glass panels;

FIG. 3 is a section taken along line 3—3 of FIG. 1 and illustrating a ceiling cornice and rail cap on which is mounted a glazing strip and stop assembly constituting a preferred embodiment of the invention for supporting the glazing beads and upper edges of the glass panels;

FIG. 4 is a section taken along line 4—4 of FIG. 1 and illustrating a left end wall cornice and rail cap on which is mounted a preferred embodiment of the inventive assembly for supporting the glazing bead and left hand edge of the left glass panel;

FIG. 5 is a section taken along line 5—5 of FIG. 1 and illustrating a right end wall cornice and rail cap having its exposed right hand side closed by a cover plate, and having a preferred embodiment of the inventive assembly mounted on its left side for supporting the glazing bead and right hand edge of the right hand glass panel;

FIG. 6 is a section taken on line 6—6 of FIG. 1 and illustrating a two part glazing divider bar assembly for supporting the opposing edges of the glass panels;

FIG. 7 is an enlarged and fragmentary, perspective view of the lower right hand corner portion of the wall section of FIG. 1, with certain parts removed for clarity, and illustrating in greater detail the manner in which the lower right hand corner of the right hand glass panel and the glazing beads thereon are supported by the floor cornice and rail cap and by a preferred embodiment of the inventive assembly;

FIG. 8 is a further enlarged and fragmentary, exploded perspective view illustrating in greater detail the structure of the glazing strip, the glazing stop and fastening means making up a preferred embodiment of the inventive assembly, together with a glazing bead and edge portion of a glass panel to be supported thereby, and

2

FIG. 9 is a view similar to FIG. 8, but illustrating a modified embodiment of the inventive assembly wherein the glazing stop "snaps on" to the glazing strip and the separate visible fastening means of FIG. 8 is eliminated.

Referring to the drawings, wherein like numerals indicate like parts, unless otherwise specified, and particularly to FIG. 1, a demountable partition wall section is generally indicated at 10. This wall section, which is of ceiling height, fills the space between the floor 11, ceiling 12 and left end wall 13 (see FIG. 4) of a building, the right end of the wall section forming part of an internal opening in the building such as a passageway, walk through or the like. Wall section 10 also has a floor to ceiling window opening in which are removably mounted a pair of preferably glass panels P.

Each of the floor 11, ceiling 12 and end wall 13 is provided with an elongated wooden furring strip 14 which is suitably secured in place by means of screws 15, as seen in each of FIGS. 2, 3 and 4. Secured over these strips 14 are the floor, ceiling and left end wall cornice and rail caps 16, which are identical in construction except that left end cap 16 is longer. The right end cap 16 of FIG. 5 is of the same construction and is the same length as the left end cap 16, but is not secured to a separate furring strip 14, as are the other caps, rather preferably to the right ends of floor and ceiling strips 14 as will be explained below.

As shown in any of FIGS. 2—5, caps 16 are each of generally channel-shaped cross-section and open to the outer sides of the rectangular frame formed thereby, as illustrated in FIG. 1. Each cap 16 includes inturned outer flange portions 17 terminating in reentrant distal flange portions 18, as well as internal lateral flange portions 19 spaced on each side of a central stepped recess portion 20. In FIGS. 2—4, the flange portions 17 abut the floor 11, ceiling 12 and end wall 13 respectively, the flange portions 18 abut the longitudinal edges of strips 14, the outer edges of the flange portions 19 abut the exposed sides of strips 14 and the recessed portions 20 similarly abut the exposed sides of strips 14, all to ensure a snug fit over these strips. In addition, in each of FIGS. 2—4, caps 16 are rigidly but removably secured in place on strips 14 by screws 21 passing through the bases of recessed portions 20.

As far as the right end cap 16 of FIG. 5 is concerned, this is preferably secured in place by passing screws (not shown) reversely through recessed portions 20 into the ends (not shown) of floor and ceiling strips 14. Moreover, the open right side of right end cap 16 is closed by a cover plate 22 preferably secured thereto by screws 23 passing through flange portions 17.

Referring briefly to FIG. 6, the wall section 10 also includes a glazing divider bar assembly generally indicated at 24 for supporting the opposing edge portions of the pair of glass panels P, as also illustrated in FIGS. 1—5. This divider bar assembly is composed of a pair of generally channel shaped members 25 and 26 each provided with inturned distal flange portions designed to abut and support the sides of panels P adjacent their opposing edges. Member 25 has a central through opening in its base and member 26 has a central internal and internally threaded nut or boss portion 27 for receiving the threaded stem of bolt 28, which is turned in the usual manner, either to tighten members 25 and 26 into engagement with panels P, or to loosen and permit removal of such members.

As will be appreciated, the various structural wall framing members described above, such as caps 16, plate 22, and divider bar members 25, 26 are preferably formed as unitary members by extruding metal. From the standpoint of economy, light weight, high strength and appearance, satin-anodized aluminum of suitable gauge has been found to be particularly adapted for use in practicing the present invention, not only in extruding the aforesaid

members, but also in extruding the preferably unitary glazing strip and stop components of the inventive assembly described below.

Referring to FIGS. 3-5, the glazing strip and stop assemblies each constituting a preferred embodiment of the invention are generally indicated at 30, and each assembly includes a glazing strip 31, a glazing stop 32 and fastening means 33. Inasmuch as the ceiling assembly 30 of FIG. 3 is identical to the end wall assemblies 30 of FIGS. 4 and 5, except in length, a description of one will suffice for all.

As best seen in FIGS. 7 and 8, and particularly FIG. 8, the elongated unitary glazing strip 31 includes an elongated flat base portion 34 having along one longitudinal edge and on one side an L-shaped salient portion facing the opposite longitudinal edge of base portion 34 and formed by lateral flange portion 35, parallel flange portion 36 and a distal lateral flange portion 37 turned inwardly toward the base portion. The flat outer lateral surface of flange portion 37 is adapted to support one side of the beaded edge portion of panel P. Base portion 34 also is provided with a rib 38 offset to the right of flange portion 37 to form one part of a two-part seat for bead B and panel P, as will be explained below.

Spaced laterally from rib 38 and located on the same side of base portion 34 adjacent its opposite longitudinal edge is another or second salient portion. This salient portion includes a first thickened wall portion defined by a longitudinal shoulder 39 and an outstanding lateral flange portion 40 having its right side wall surface covered with a plurality of longitudinal serrations 41. The second salient portion is completed by a second thickened wall portion defined by a longitudinal shoulder 42 merging with the adjacent longitudinal edge of base portion 34 and an outstanding lateral flange portion 43 like flange portion 40, but having only a single longitudinal "starter" serration 44 on its left side wall surface adjacent its outer edge. These spaced and opposed, inner lateral serrated surfaces of flange portions 40 and 43, together with the side of base portion 34 form a channel shaped recess for receiving the fastener 33 preferably of the machine screw type, and the outer or opposite smooth side walls of these flange portions form spaced and oppositely facing flat outer lateral surfaces parallel with the outer surface of flange portion 37 for engagement with stop 32 which is adapted to support the other side of the beaded edge portion of panel P.

In addition, the portion of shoulder 39 adjacent rib 38 forms the second part of the two-part seat for bead B on panel P. The purpose of this construction is to avoid points of stress concentration caused by seating bead B on the heads of screws 45 securing the strips 31 to caps 16 (FIGS. 3-5), just as the stepped recess functions for the same purpose in FIG. 2.

Continuing with FIG. 8, the glazing stop 32 of the inventive assembly 30 is generally channel-shaped in cross-section and opens toward the second or right hand salient portion of strip 31. Stop 32 includes a base portion 46 having a series of longitudinally spaced openings 47 (only one being shown), and a pair of lateral flange portions 48 each terminating in inturned distal lug portions 49 having rounded ends or edges for sliding engagement with the outer surfaces of flange portions 40 and 43. When installed, the outer side of left flange portion 48 forms a flat, outer lateral surface parallel with the outer surface of flange portion 37 for properly supporting the other or adjacent side of the panel edge portion.

The inventive assembly 30 is completed by the desired number of screw type fasteners 33. In assembling stop 32 on strip 31, the stop is slid laterally over the second salient portion, with the rounded ends of lug portions 49 engaging the outer side walls of flange portions 40, 43. The fasteners 33 are passed through openings 47 and turned so that their threaded stem portions engage serrations 41 and 44, biting into these serrated surfaces. So

long as one of the opposed inner surfaces of flange portions 40, 43 is provided with a plurality of longitudinal serrations 41, it is only necessary that the other surface be provided with a single or "starter" serration 44 adjacent its outer edge to ensure proper tightening of a fastener 33. This substantially reduces manufacturing costs.

Referring now to FIG. 9, a modified embodiment of the invention is generally indicated at 50, and in this instance, the assembly is composed of only two unitary components, the glazing strip 51 and the stop 52. As in the embodiment of FIG. 8, the substantially flat base portion 53 includes a first salient portion adjacent one longitudinal edge, this portion being preferably L-shaped in cross-section, opening toward the opposite longitudinal edge and formed by lateral flange portion 54, parallel flange portion 55 and distal lateral flange portion 56 turned inwardly toward the base portion, and corresponding to flange portions 35, 36 and 37 respectively in FIG. 8. However, strip 51 differs in that it has no rib 38 and does not provide a raised seat for bead B and panel P. Moreover, the second or right hand salient portion differs from that of FIG. 8 in that it is formed by a single thickened wall portion or boss 57 of generally "mushroom" or T shape in cross-section and terminating in outstanding and oppositely facing, longitudinal flange or ear portions 58 and 59, which have inner and flat, longitudinal surfaces perpendicular to the flat outer lateral surface of flange portion 56. Flange portions 58 and 59 form with the adjacent side of base portion 53 outwardly facing longitudinal recesses 60 and 61 having oppositely facing and flat, inner lateral surfaces which are parallel with the outer lateral surface of flange portion 56, and together with the inner longitudinal surfaces of flange portions 58, 59, are engageable with glazing stop 52 for supporting the other beaded side of panel P.

Continuing with FIG. 9, the stop 52 is much like stop 32 of FIG. 8 in that it is composed of base portion 62, side flange portions 63 and inturned distal lug portions 64 having rounded ends or edges, and when installed, the flat outer surface of left flange portion 63 is parallel to the outer surface of flange portion 56 for properly supporting panel P. However, unlike stop 32, base portion 62 needs no openings 47, and flange portions 63 are wider than flange portions 48 to compensate for the absence of shoulders 39 and 42 of FIG. 8, since in each embodiment it is desired that the base portion of the stop be flush or coplanar with flange portion 36 (FIG. 8) and 55 (FIG. 9) for evenly supporting both sides of panel P.

Moreover, stop 52 is of the "snap on" type instead of the "screw on" type, as is stop 32. In this instance, the flange portions 58 and 59 span a distance greater than the distance between lug portions 64. However, because of the natural resiliency of flange portions 63, they readily spring apart when forcing lugs 64 of stop 52 over flange portions 58, 59, and readily spring lugs 64 back into engagement with the inner surfaces of recesses 60 and 61 to securely latch stop 52 in place on strip 51. The rounded contours of lug portions 64 and of the outer edges of flange portions 58, 59 facilitate such assembling, while the radius of curvature of flange portion 59 is greater than that of flange portion 58 and arranged to form a more pointed juncture with the adjacent side wall of recess 61 in order to prevent accidental removal of stop 52. At the same time, the right flange portion 63 is designed to project slightly beyond the adjacent longitudinal edge of base portion 53 to facilitate prying stop 52 loose, with an appropriate tool, such as a screwdriver (not shown).

While the glazing bead B has been referred to briefly above, it is to be understood that this is merely the preferred bead in that it can be readily extruded to length from suitable plastic material such as rigid polyvinyl chloride. Thus, as best seen in FIGS. 8 and 9, bead B is comprised of a flat base portion b having inner converging leg portions c merging with more steeply converging outer leg portions d terminating in reversely bent and oppositely

diverging wing portions *e*. Normally, the distance between inner leg portions *d* is less than the thickness of panel *P*, but these leg portions can be readily sprung apart to snap or slide bead *B* in place over the edge portion of panel *P*.

In erecting a wall section such as 10, as indicated in FIG. 1, the caps 16 are appropriately secured in place on strips 14 to form the rectangular frame, as noted previously. Next, one or more of strips 31 or 51 may be secured to the appropriate caps 16 to complete the window opening. If more than one wall section is to be erected, it will be apparent that this may be done without regard to installation of panels such as *P*, which can wait until the end. Thus, when desired, the panels *P* may readily be installed in place by inserting their beaded lower edges in recess 20 in floor cap 16 (FIG. 2), after which the stops 32 or 52 are assembled on strips 31 or 51 respectively, to secure the panels *P* in place. Preferably, the ceiling stop is installed first in wall section 10, as this will support the upper edges of both panels *P*, whereupon the installation of the left and right end wall stops may be accomplished as desired. The wall section 10 is completed by assembling divider bar channel members 25 and 26 of FIG. 6 on opposite sides of the opposing panel edge portions and tightening bolt 28.

It will now be seen how the invention accomplishes its objects, and the numerous advantages of the invention likewise will be apparent. While the invention has been described and illustrated herein by reference to certain embodiments, it is to be understood that various changes and modifications may be made therein by those skilled in the art, without departing from the inventive concept, the scope of which is to be determined by the appended claims. For example, to improve appearance and further reduce the visibility of fasteners 33, the holes 47 in stops 32 could be countersunk. Likewise, if desired, the insertion of panels *P* into recess 20 of floor cap 16 (FIG. 2) could be completely eliminated by attaching thereto either embodiment of the inventive assembly.

What is claimed is:

1. A glazing strip for removably supporting a wall panel, such as a glass panel, and comprising substantially flat base means, first salient means on one side of said base means and having substantially flat, first lateral surface means for supporting one side of a panel, and second salient means on said one side of said base means, said second salient means having oppositely facing and substantially flat outer lateral surface means substantially parallel with said first lateral surface means and engageable with a glazing stop for supporting the other side of said panel, and opposed inner lateral serrated surface means arranged between said outer lateral surface means and engageable with threaded fastening means for removably securing said stop on said strip.

2. An elongated unitary glazing strip for removably supporting a wall panel, such as a glass panel, and comprising a substantially flat base portion, a first generally L-shaped salient portion on one side of said base portion adjacent one longitudinal edge thereof, facing the opposite longitudinal edge thereof and including an inwardly turned distal flange portion forming a substantially flat, first lateral surface for supporting one side of a panel, and a second salient portion on said one side of said base portion adjacent said opposite longitudinal edge, said second salient portion having a spaced pair of oppositely facing and substantially flat, outer lateral surfaces substantially parallel with said first lateral surface and engageable with a glazing stop for supporting the other side of said panel and a spaced pair of opposed inner lateral serrated surfaces arranged between said outer lateral surfaces and being engageable with a threaded fastener for removably securing said stop on said strip.

3. The glazing strip of claim 2 wherein one of said inner surfaces is covered with a plurality of longitudinal serrations, and the other of said inner surfaces has a single longitudinal serration adjacent its outer edge.

4. An elongated unitary glazing strip for removably supporting a wall panel, such as a glass panel, and comprising a substantially flat base portion, a first generally L-shaped salient portion on one side of said base portion adjacent one longitudinal edge thereof, facing the opposite longitudinal edge thereof and including a distal flange portion turned inwardly toward said base portion and forming a substantially flat, first lateral surface for supporting one side of a panel, and a second salient portion on said one side of said base portion adjacent said opposite longitudinal edge, said second salient portion including a mushroom-shaped lateral flange portion terminating in outstanding oppositely facing longitudinal flange portions which have inner and substantially flat, longitudinal surfaces substantially perpendicular to said first lateral surface, and said lateral flange portions forming with said one side of said base portion outwardly facing recesses having oppositely facing and substantially flat, inner lateral surfaces which are substantially parallel with said first lateral surface and, together with said inner longitudinal surfaces, are engageable with a glazing stop for supporting the other side of said panel, the outer edges of said longitudinal flange portions being rounded to facilitate engagement with said stop, but the outer edge of the one of said longitudinal flange portions adjacent said opposite longitudinal edge of said base portion having a greater radius of curvature than the other outer edge and being arranged to merge with its inner longitudinal surface in a sharper juncture to prevent accidental removal of said stop.

5. A glazing strip and stop assembly for removably supporting a wall panel, such as a glass panel, and comprising in combination, a strip including substantially flat base means, first salient means on one side of said base means and having substantially flat, first lateral surface means for supporting one side of a panel, and second salient means on said one side of said base means, said second salient means having oppositely facing and substantially flat, outer lateral surface means substantially parallel with said first lateral surface means and opposed inner lateral serrated surface means arranged between said outer lateral surface means, a stop of generally channel shape facing said second salient means, having means engageable with said outer surface means and having substantially flat, third lateral surface means facing and substantially parallel with said first lateral surface means for supporting the other side of said panel, and fastener means engageable with said stop and inner serrated surface means for removably securing said strip and stop together.

6. A glazing strip and stop assembly for removably supporting a wall panel, such as a glass panel, and comprising in combination, an elongated unitary glazing strip including a substantially flat base portion, a first generally L-shaped salient portion on one side of said base portion adjacent one longitudinal edge thereof, facing the opposite longitudinal edge thereof and including an inwardly turned distal flange portion forming a substantially flat, first lateral surface for supporting one side of a panel, and a second salient portion on said one side of said base portion adjacent said opposite longitudinal edge, said second salient portion having a spaced pair of oppositely facing and substantially flat, outer lateral surfaces substantially parallel with said first lateral surface and a spaced pair of opposed, inner lateral serrated surfaces arranged between said outer lateral surfaces and an elongated unitary glazing stop of generally channel shape and including a base portion having longitudinally spaced through openings, and a pair of outstanding flange portions facing said second salient portion, said flange portions having inner surface means engageable with said outer lateral surfaces, and one of said flange portions having an outer lateral surface facing and substantially parallel with said first lateral surface for supporting the other side of said panel, and a plurality of threaded fasten-

ers passing through said openings and engageable with said serrated surfaces for removably securing said strip and stop together.

7. The glazing strip and stop assembly of claim 6 wherein one of said inner surfaces is covered with a plurality of longitudinal serrations and the other of said inner surfaces has a single longitudinal serration adjacent its outer edge.

8. A glazing strip and stop assembly for removably supporting a wall panel, such as a glass panel, and comprising in combination, an elongated unitary strip including a substantially flat base portion, a first generally L-shaped salient portion on one side of said base portion adjacent one longitudinal edge thereof, facing the opposite longitudinal edge thereof and including a distal flange portion turned inwardly toward said base portion and forming a substantially flat, first lateral surface for supporting one side of a panel, and a second salient portion on said one side of said base portion adjacent said opposite longitudinal edge, said second salient portion including a mushroom-shaped lateral flange portion terminating in outstanding and oppositely facing, longitudinal flange portions which have inner and substantially flat, longitudinal surfaces substantially perpendicular to said first lateral surface, and said longitudinal flange portions forming with said one side of said base portion outwardly facing and substantially flat, recesses having oppositely facing inner lateral surfaces substantially parallel with said first lateral surface, and a stop of generally channel shape and including a base portion, a pair of outstanding lateral flange portions facing said second salient portion and terminating in inwardly bent distal lug portions opposing each other, said outstanding lateral flange portions being springable apart for forcing said lug portions into engagement with said inner longitudinal and lateral surfaces of said mushroom-shaped flange portion for removably securing said strip and stop together, and one of said outstanding lateral flange portions having an outer

surface facing and substantially parallel with said first lateral surface for supporting the other side of said panel, the outer edges of said longitudinal flange portions of said mushroom-shaped flange portion being rounded to facilitate engagement with said stop, but the outer edge of the one of the longitudinal flange portions adjacent said opposite longitudinal edge of said base portion having a greater radius of curvature than the other edge and being arranged to merge with its inner longitudinal surface in a sharper juncture to prevent accidental removal of said stop, and the other of said outstanding flange portions of said stop being arranged to project beyond said opposite longitudinal edge of said base portion to facilitate removal of said stop from said strip.
